Des. 216,414
Patented Dec. 30, 1969

216,414

ILLUMINABLE MIRROR

Stanley E. Hanson, 2730 Maverick Ave.,
Anaheim, Calif. 92805

Filed Sept. 18, 1968, Ser. No. 13,589

Term of patent 14 years

Int. Cl. D28—03

U.S. Cl. D86—10

FIG. 1.

FIG. 2.

FIG. 3.

FIG. 1 is a front elevational view of an illuminable mirror showing my new design with the mirror in a tilted position, the side opposite being substantially similar thereto;

FIG. 2 is a side elevational view thereof; and

FIG. 3 is a top plan view.

I claim:

The ornamental design for an illuminable mirror, as shown and described.
